UNITED STATES PATENT OFFICE.

WILLARD G. STAPLES, OF NEWBURYPORT, MASSACHUSETTS, ASSIGNOR TO FEDERAL METALLIC PACKING COMPANY, OF BOSTON, MASSACHUSETTS, A CORPORATION OF MASSACHUSETTS.

METAL-STRAND MACHINE.

1,063,895.

Specification of Letters Patent.

Patented June 3, 1913.

Application filed October 10, 1911. Serial No. 653,948.

To all whom it may concern:

Be it known that I, WILLARD G. STAPLES, a citizen of the United States, residing at Newburyport, county of Essex, and State of Massachusetts, have invented a new and useful Improvement in Metal-Strand Machines, of which the following is a specification, reference being had to the accompanying drawings.

10 This invention relates to machines for making metallic strands, filaments or bands in which the strands, etc. are formed by throwing a stream of molten metal upon a moving surface and in which the strands are arranged and assembled in bundles of suitable length and is an improvement of the invention shown and described in Letters Patent No. 989,075, dated April 11, 1911.

15 Metallic strands or filaments are employed 20 to a large extent in packing joints, valve stems and piston-rods and similar devices and when so used a large number of strands or filaments are bunched together in substantial parallelism or twisted into rope 25 form. It is essential in such cases that the metallic strands or filaments be arranged substantially parallel to each other and the object of this invention is to provide means for arranging the continuous strand or filament, as it is thrown off the moving surface, 30 into bundles of suitable length.

35 In the accompanying drawings illustrating the preferred form of my invention, Figure 1 is a plan view of an apparatus constructed and operated in accordance with my invention; Fig. 2 is a front elevation of the same, looking upwardly in Fig. 1; Fig. 3 is a side elevation of the upper portion of the same looking from right to left in Fig. 1; 40 Fig. 4 is a detail elevation partly in section, on an enlarged scale of the means for feeding the molten metal to the moving surface to form the continuous strand, and Figs. 5 and 6 are detail views in elevation and plan 45 respectively.

In the illustrated embodiment of the invention, the strand forming mechanism comprises a reservoir 7 for molten metal and a rotatable disk 8. The reservoir may be supported in any suitable frame 9 on a table or bench 10 which serves as a supporting frame for the machine. Underneath the reservoir may be arranged a gas burner 11 to maintain the metal in a molten condition and the

metal is delivered through a spout 12 to the 55 edge 13 of the disk, the flow of the metal being controlled by a valve 14. A gas burner 15 is arranged to heat the nozzle to prevent the metal cooling as it flows out. To permit of rotation of the disk 8, it is 60 mounted on a shaft 16 supported at the base in a step bearing 17 and journaled in a box-bearing 18, the shaft being provided with a pulley 19 which is connected by a belt 20 with any suitable driving means. The edge 65 13 of the disk is cut away to form a grooved channel 21 which in cross-section may be angular or curved to produce strands of varying form in cross-section. When the disk is rotated and molten metal is allowed 70 to flow through the nozzle, it strikes the edge of the disk in the channel 21 and is cooled by contact therewith and thrown from the rotating disk by centrifugal force in the form of a continuous strand or fiber. The 75 size of the strand is regulated by adjusting the valve in the nozzle to control the amount of flow of the metal and the shape of the strand in cross-section is determined by the cross-sectional form of the channel. By 80 these means strands of various sizes and cross-sectional forms may be produced and the edge of the disk may be provided with a number of channels of varying cross-section, 85 which may be used by adjusting the nozzle. As shown in Fig. 4, the point of the nozzle is arranged in close proximity to the channel in the disk edge.

For the purpose of gathering and arranging the strand in substantial parallelism and in bunches of suitable length, I provide the following mechanism. On the table 10 is pivotally mounted at 22 a rod 23 carrying on its free end a downwardly projecting hook 24 which is preferably spoon-shaped and curved inwardly. Means are provided for swinging the rod around its pivot into the path of the strand 25 as it is thrown from the disk 8, (see Fig. 1), and then back to carry the strand 90 over a horizontal right angled rod 26 mounted in the front edge of the table 10 where the strand is deposited. Any suitable means 95 may be employed for operating the swinging rod 23 and one such device is shown in the drawings and comprises an eccentric 27 mounted on a shaft 28 supported in suitable bearings 29 on the table 10. The eccentric

has a grooved perimeter 30 and the rod is held in said groove by an upright spring rod 31 moving in a guideway 32 and connected to the swinging rod by a cord 33. The eccentric is operated from the shaft 16 by means of pulleys 34 and 35 on the shafts 16 and 28 respectively and a belt 36. The eccentric is so arranged that the swinging rod is above the disk 8 and oscillates over it to lay the strand in a series of loops to form a bundle 37 on the rod 26.

In practice my machine is operated in the following manner. The burners 11 and 15 are lighted and when the metal in the reservoir has been reduced to a molten state, the machine is started in operation by means of the belt 20 connected to the driving means. The shaft 16 and disk 8 are thereby rotated, the direction of rotation of the latter being in the direction taken by the strand 25 as shown in Fig. 6. By opening and regulating the valve 14 a thin stream of molten metal is allowed to flow from the mouth of the nozzle 12, which is in close proximity to the channel 21 in the edge of the disk, and as the stream of metal strikes the moving edge of the disk it is cooled, solidified and thrown therefrom in the form of a metallic strand or fiber which is continuous in form so long as the stream of metal is uninterrupted. As heretofore stated the size of the strand may be varied by changing the volume of flow of the metal and its cross-sectional configuration may be modified by using channels of various cross-sectional forms. As shown in Figs. 1 and 3 the strand is thrown from the disk in a tangential direction and horizontally with considerable force.

At the same time that the strand forming disk 8 is rotated, the eccentric 27 mounted on the shaft 28 is turned by the belt 36 and thereby the rod 23 which is held in the groove on the perimeter of the eccentric by the spring 31 and cord 33 is caused to oscillate. The spring 31 is at all times under tension and maintains the rod in place against the eccentric. In Fig. 1 the full lines show the position of the rod when about to engage the strand 25 and the dotted lines show its position after it has completed its oscillating movement and has dropped the strand on the support 26. As the rod oscillates toward the reservoir the curved hook 24 slides over the metal strand but when it returns the hook catches the strand and carries it toward the rod or support 26, permitting it to drop thereon as it (the rod) starts back toward the reservoir. Figs. 5 and 6 illustrate this operation and the manner in which the strand is carried by the hook. During this operation the strand is being continuously formed and remains unbroken, the result being that it is hung over the support in a series of loops as illus-

trated in Fig. 2. After a sufficient number of loops have been assembled together, the bundle is removed from the support and may be cut. The length of the bundle thus secured may be varied by changing the speed of the oscillating rod which may be accomplished by changing the relative sizes of the pulleys 34 and 35.

While the preferred embodiment of the present invention has been illustrated and described, it is to be understood that the present invention is not limited to the exact details of construction shown and described but may be otherwise embodied within the spirit of the invention and the scope of the following claims.

What I claim is:

1. In apparatus of the character described, the combination with means for forming and delivering a continuous metal strand of an oscillating member for laying said strand over a suitable support in loops of suitable length.

2. In apparatus of the character described, the combination with means for forming and delivering a continuous metal strand of an oscillating member provided with means for engaging said strand and means for oscillating said member to lay said strand over a support in loops of suitable length.

3. In apparatus of the character described, the combination with means for forming and delivering a continuous metal strand of an oscillating member provided with a curved end for engaging and carrying said strand, a support and means for oscillating said member to lay said strand over said support to form loops of suitable length.

4. The combination with a strand forming mechanism of a rod pivotally mounted and having a hook on its free end for catching said strand as it is formed, means for oscillating said rod between the path of said strand and a support in order alternately to catch and to deposit said strand in loops upon said support.

5. The combination with a strand forming mechanism of an oscillating member, an eccentric engaging said member and means for rotating said eccentric to oscillate said member.

6. The combination with a strand forming mechanism of an oscillating member, an eccentric engaging said member, means for holding said oscillating member in engagement with said eccentric and means for rotating said eccentric to oscillate said member.

7. The combination with a strand forming mechanism of an oscillating member provided with a curved end to engage said strand as it is formed by said mechanism and means for oscillating said member in order to carry said strand over a support

and to drop it upon said support in successive operations.

8. The combination with a strand forming mechanism of a rod pivotally mounted and having its free end provided with a hook, an eccentric engaging said rod to oscillate it, means for holding said rod in engagement with said eccentric and means for rotating said eccentric to oscillate said

rod into the path of said strand as it is thrown from the strand forming mechanism.

In testimony whereof, I hereunto set my hand in the presence of two subscribing witnesses, this the fourth day of October, 1911.

WILLARD G. STAPLES.
